ATTORNEY

UNITED STATES PATENT OFFICE.

WILLIAM H. GRINDLEY, OF COUGLETON, ENGLAND, ASSIGNOR TO WILLIAM S. PITCAIRN, OF NEW YORK, N. Y.

DESIGN FOR A COVERED DISH.

SPECIFICATION forming part of Design No. 33,281, dated October 2, 1900.

Application filed September 8, 1900. Serial No. 29,460. Term of patent 34 years.

To all whom it may concern:

Be it known that I, WILLIAM H. GRINDLEY, a subject of the Queen of Great Britain, residing at Cougleton, county of Chester, England, have invented a new and original Design for a Covered Dish; and I do declare the following to be a full, clear, and exact description of the same, reference being had to the accompanying drawings, forming a part hereof.

In the drawings, Figure 1 is a perspective view of the covered dish embodying my design, and Fig. 2 is a top view of the same.

The body of the dish is oblong or oval. Its upper rim forms a continuous smooth curve. It is provided at each extremity with a handle, and it narrows rapidly toward its base, where it is expanded into a foot, which is scalloped along its rim.

Immediately beneath the upper rim of the body of the dish is arranged a series of embossed ornamentalations, consisting of a curve *a*, terminating in an inwardly-curved bead or circle *b* at each end and alternating with a trifoliate figure *c*, pointing inward. Near the foot is a row of short embossed lines *d*. Between these two rows of ornamentalations is a row of embossed ornamentalations, consisting of a trifoliate figure *e* and a quadrifoliate figure *f*. Alternately arranged between each pair of these figures *e* and *f* is a conventionalized stalk *g*, provided with flowers *h*, the top of the same in each case being toward the figure *f* and away from the figure *e*.

The cover of the dish is similar in outline to the upper rim of the body of the dish, into which it fits and which it overlaps. It is raised toward the center, where it is provided with a handle. Its outer rim forms a continuous smooth curve. Immediately within the rim is arranged a series of embossed ornamentalations, consisting of a curve *a'*, terminating in an inwardly-curved bead or circle *b'* at each end and alternating with a trifoliate figure *c'*, pointing inward. Toward the raised middle portion is a row of short embossed lines *d'*. Between these two rows of ornamentalations is a row of embossed ornamentalations, consisting of a trifoliate figure *e'* and a quadrifoliate figure *f'*. Alternately arranged between each pair of these figures *e'* and *f'* is a conventionalized stalk *g'*, provided with flowers *h'*, the top of the same in each case being toward the figure *f'* and away from the figure *e'*. 55

What I claim is—

The design for a covered dish substantially as shown and described.

In testimony whereof I have hereunto affixed my signature, in the presence of two witnesses, this 21st day of August, 1900.

WILLIAM H. GRINDLEY.

Witnesses:

J. H. COPESTAKE,
WM. HARRISON BRADLEY.
